UNITED STATES PATENT OFFICE.

THOMAS H. GIGNILLIAT, OF SAVANNAH, GEORGIA.

AEROPLANE FLYING-MACHINE.

No. 906,406.

Specification of Letters Patent.

Patented Dec. 8, 1908.

Application filed December 13, 1906. Serial No. 347,672.

To all whom it may concern:

Be it known that I, THOMAS H. GIGNILLIAT, a citizen of the United States, residing in Savannah, county of Chatham, and State 5 of Georgia, have invented certain Improvements in Aeroplane Flying-Machines, of which the following is a specification.

My invention relates to aeronautic machines and more especially to that type of 10 flying machines designated as aeroplanes.

The object of my invention is to enable men to soar in the air, and to this end, my invention consists of one or more main or soaring aeroplanes of a peculiar construction, 15 propelled by a plurality of smaller aeroplanes, as hereinafter described, with reference to the accompanying drawings, and particularly pointed out in the claims.

In the drawings:—Figure 1 is a diagrammatic rear elevation of the complete machine, the propelling aeroplanes being operated by a small motor; Fig. 2 is a plan view; Fig. 3 is an end view of the same, showing the machine on launching chute; Fig. 4 is a diagrammatic rear elevation of a modification, 20 showing the propelling aeroplanes operated by foot; Fig. 5 is a plan view thereof; Fig. 6 is an end view thereof; Fig. 7 is a perspective view, some of the smaller aeroplanes on 25 the right hand side being dropped down to show the frame; Fig. 8 is a detail plan view of the platform; Fig. 9 is a detail view of one of the supporting wheels of the platform; Fig. 10 is a detail of the framing, showing 30 diagonal bracing with wires; Fig. 11 is a detail plan view of a modified arrangement of the smaller aeroplanes; and Fig. 12 is a perspective detail showing the effect of the air pressure on the top of the smaller aeroplanes.

Referring to the drawings, in which the same reference characters refer to the same parts in all views, the letter A represents fixed, main or soaring aeroplanes of the box kite variety, and F, F² and F³, represent the 40 well known box kite frame belonging to the same, made of aluminum, wood or other suitable material, possessing sufficient lightness, combined with the requisite strength. The two middle pairs of vertical standards F 45 of this frame, are longer than any of the others, and extend upwards and downwards, as shown. From the upper extremities of these standards run guys G to the extremities of the aeroplanes A for the purpose of 50 supporting the same. On the lower extremities of the prolonged vertical standards

F is attached a platform c, to which are attached suitable axles, carrying wheels E. Two other pairs of vertical standards F of the main aeroplane frame extend downwards on each side of the platform c and are braced by guys H to the said platform, and by guys K to the ends of the main aeroplanes, so as to add the strength of the whole structure, all as shown in Figs. 1, 3, 4 and 7. 60 The upper extended portion of the two middle pairs of vertical standards F are connected by rods L which are detachable, and are provided with hinges M near the main aeroplane. By detaching the rods L and 65 swinging the extended portion of the two center frames F outward and downward to the positions shown by the dotted lines F', Fig. 4, the machine becomes more compact 70 and can be more readily housed. The vertical standards F are connected by fore and aft ties F², placed at suitable intervals as required to furnish sufficient strength to the structure. These horizontal fore and aft strips F² extend both forward and back of 75 the vertical standards F for the purpose of supporting the extended portions of the aeroplanes A, as shown in Figs. 2, 5, 7, and 9.

In the main form of my invention, designed to be operated by a small motor O, of 80 suitable type, the horizontal fore and aft strips F² extend far enough back to support secondary fixed aeroplanes B', which are placed far enough to clear the propeller N, and serve to balance the weight of the motor 85 O, as shown in Figs. 1, 2 and 3.

Each pair of vertical standards F, together with the horizontal fore and aft ties F² forms a square flat frame. These are connected together by stringers F³, running from side 90 to side, as shown in Figs. 1, 2, 4, 5 and 6. Thus an open box kite frame is formed, upon which the aeroplanes are secured. The open box kite frame thus formed is strengthened by diagonally bracing every square with 95 wire, including all those squares shown in the side elevation and plan, as well as those shown in front and rear elevation, as shown clearly in Fig. 10. Screws P are set into the frame near the corners, with their heads 100 slightly projecting. Around these projecting heads, the wire braces R are twisted and then drawn taut diagonally across the openings. Any slack left in the diagonal wire braces R after it is thus stretched, is taken 105 up by other adjusting wires R², stretched from the center of said diagonal wire brace R

to the corresponding diagonal wire brace on the opposite side of the box kite frame, or by some other convenient adjusting device.

As shown in Fig. 7, the large fixed soaring aeroplanes A are made up of a number of smaller underlapping aeroplanes e. The said smaller aeroplanes e consist of strips of cloth or other suitable material, tacked or otherwise secured to one edge of spline of wood or other suitable material, which stiffen the said smaller aeroplanes. The edges which have the splines s tacked to them are thus rendered more rigid than the other edge of the said smaller aeroplanes e, and when the wind blows on top of the said small aeroplane, the free edges bend down and causes it to spill the wind, and each of the free edges of the small aeroplanes e, bending downwards, the large aeroplanes A, B and B', which are composed of smaller aeroplanes e, are broken up into a number of surfaces, and, thus, do not receive the force of the wind. In Fig. 7 these smaller aeroplanes e are shown running from front to back. They may run from side to side, if desired, as shown in Fig. 11, or at an angle. The essential feature of this part of the invention is that the said smaller underlapping aeroplanes e be so arranged that they shall close together and form one continuous surface, as shown in Fig. 7, when the air presses on the underside, and that they shall separate and form a number of surfaces and let the air spill between them, when the air presses on the top side, as shown in Fig. 12.

Those splines s, extending back past the vertical standards F to the rear, (see Fig. 12) are tapered toward their after ends, as shown. This causes the after ends of said splines s and also the small attached aeroplanes e, to bend upwards when the wind presses on the under side of said small aeroplanes. Since the large aeroplanes A, B and B' are made up of the small aeroplanes e, when the wind presses on the under side of the flying machine, the after edges of all the said large aeroplanes, A, B and B', bend upwards. The pressure thus produced can be resolved into two parts, one of which is forward. Thus, the flying machine must have a forward motion whenever the air presses on the under side of same. The air always presses on the under side of the machine when descending. It, therefore, follows that whenever my flying machine is descending, it will have a forward, as well as a downward motion. This adds to the usefulness of my invention, as it removes the danger which attends aeroplanes, in case they lose their forward motion and become unmanageable from consequent loss of steering power, and the danger from a broken propelling mechanism is also lessened; my machine will always retain its forward motion, and, therefore, its manageability

until it touches ground. The amount of surface exposed to the action of the air can be so proportioned to the weight, that the downward velocity will not be dangerous. Running across the backs of the splines s, which extend to the rear and secured to them with a strong thread or by other suitable means, are long thin stringers a, which keep the after ends of the splines all on the same level, and make them mutually strengthen each other. The splines s are so spaced in every instance, that the distance between them is less than the width of the attached aeroplanes e. The loose edges of each of the small aeroplanes e hang down and underlap the splines s of each of the adjoining small aeroplanes e. When the air blows up against them, they rise and close against the under sides of the adjoining splines s. The splines s and stringers a support them so that they cannot slip up between the splines s. They thus form a continuous surface and unite to make the large aeroplane A, B and B'.

As shown in Figs. 4 and 6, in the form of machine operated by foot power, the propelling aeroplanes B are connected with the main body of the machines by rods P²; the forward ends of which are hinged to the forward parts of the main frame, the lower pair of rods being fitted with a cross-bar R³ also serves as a pedal by which the operator presses the aeroplanes B down with his foot. The upper pair of rods P² are connected with the lower pair of rods by vertical rods which are hinged at both upper and lower ends of the said rods P², and which, therefore, cause the upper and lower rods P², to move simultaneously up and down, and to keep parallel to each other. Attached to the lower aeroplane B are two small wheels which keep same clear of the ground when the aeroplane is on the ground.

In Fig. 6 the propelling aeroplanes B are shown in their upper position and, when pressed down by the operator pressing his foot on cross-bar R³, they are in a position shown by the dotted lines, and the rods P² take the positions shown by dotted lines. After the operator presses the aeroplanes B down to their new positions they are drawn up again to their old positions B by elastic straps U, (see Fig. 6), which are secured at their lower ends to the bars P² and at their upper end to the main frame of the aeroplane.

The machine is steered in an up and down direction by the operator balancing himself on the platform. It is steered to the right or left by the rudders Z at either side of the machine, (see Figs. 2 and 5), hinged to the frame of the main aeroplane at X. They have cords or rods W attached to their after edges and leading from there to the platform for the operator. When the operator pulls

on the cord or rod W, to the right, the rudder at that end of the machine is swung so as to make an angle with the line of motion of the machine. This drags that end of the machine 5 and causes the aeroplane to swing around in that direction. The machine is likewise turned in the opposite direction if the operator pulls on the cord or rod W to the left. The chute Y is built at an incline sharp 10 enough to give the flying machine the requisite velocity for the start. The lower end is tipped up as shown, so that the aeroplane is moving in a direction inclined upwards at the moment of leaving the chute.

15 The method of operating my flying machine is as follows:—The flying machine is placed on the chute Y and the operator takes his place on the platform c. He allows the machine to run freely down the said chute on 20 the wheels E. As the flying machine gets to the lower end of the chute, the upward inclination of this end of the chute causes the flying machine to change from a downward glide to an upward glide and it leaves the 25 chute with a gliding motion having an upward inclination in the air. This motion acquired by the speed of the machine on the incline under the force of gravity is continued by the use of the propelling power, either foot 30 power or the motor, as shown. The wheels E not only serve as rollers on which the flying machine runs down the chute, but also for the purpose of landing the machine on the ground without damage at the end of the 35 flight. The front wheels E are of greater diameter than the after wheels, thus causing the aeroplanes to be inclined to the line of motion and the air to press on their under side whenever the flying machine is rolling on 40 the said wheels E. On the way down the chute, the rollers 7, on the sides of the platform c, (see Figs. 8 and 9), take against the side pieces 8, of the chute Y and keep the flying machine from running off the said 45 chute. When nearing the ground at any time, should the flying machine tip to one side or the other, the wheels V at either end of the machine roll along the ground and thus prevent the machine from being damaged by a sudden stop or jar at one end.

50 In working the foot power the operator presses down on the cross-bar R³, this presses the aeroplanes B downwards and backwards, causing a resultant pressure forward and upwards, which propels the machine through the air. The forward resultant of this pressure is increased by the fact that the after edges of the aeroplanes B are flexible. This causes the said after edges to bend upwards 55 as the said aeroplanes B are pressed downwards, and the pressure on their after edges becomes almost directly forward, and causes the whole flying machine to move in a forward direction.

60 65 When the pressure is applied to the cross-

bar R³, the elastic straps U are stretched out by the downward motion of the rods P², and when the pressure is withdrawn from the cross-bar R³, the said rubber straps U contract and draw the said rods P² and the attached aeroplanes B back to their original position ready for another stroke. Should the operator wish to ascend, he moves a little backward and causes the aeroplanes to tip upwards, this will result in the whole flying 70 machine gliding upwards; should he wish to descend he moves a little forward, this causes the aeroplanes to tip down in front and the machine glides down. Should the operator tip the machine so far down in front as to cause the air to strike the aeroplanes A on top instead of underneath, the small aeroplanes e separate, as shown in Fig. 12, and the wind spills between them. The center of gravity being near the platform that part of 75 the machine instantly swings under the light super-structure and the machine thus automatically rights itself and the pressure returns instantly to the under side of the aeroplanes where it should be. If the operator wishes 80 to steer to the right he pulls on the right tiller rope W, which swings the rudder Z on that side of the machine at an angle with the line of motion and causes a drag on that side of the machine, which swings the whole flying 85 machine in that direction. If the operator wishes to steer to the left he pulls on the left tiller rope or rod W and leaves the right tiller rope alone.

I claim as my invention:—

1. In a flying machine, the combination of one or more fixed aeroplanes, each composed of a number of smaller flexible aeroplanes, adapted to close together and form one continuous surface when the wind presses on the under side, and to open and form a number of separate surfaces when the wind blows on the top side, separate splines to which said smaller aeroplanes are attached, and stringers crossing said splines, whereby the free edges of said flexible aeroplanes are prevented from slipping between the splines when the wind presses on the under sides, and propelling mechanism, substantially as described.

2. In a flying machine, the combination of one or more fixed aeroplanes each composed of a number of smaller aeroplanes adapted to close and form together a continuous surface when the air presses on the under side, and to open and form a number of separate surfaces when the air presses on the top side, separate splines to which said smaller aeroplanes are attached, and stringers crossing said splines, whereby the free edges of said flexible aeroplanes are prevented from slipping between the splines when the wind presses on the under sides, the after edges of the said fixed aeroplanes adapted to bend upwards when the wind presses on the under

- side, and propelling mechanism, substantially as described.
3. In a flying machine, the combination of one or more fixed aeroplanes, with a plurality of propelling aeroplanes provided with a number of smaller aeroplanes, adapted to open and close, the after edges of said propelling aeroplanes being adapted to bend upwards under the pressure of upward currents of air, substantially as described. 45
4. In a flying machine, the combination of one or more fixed aeroplanes, with a plurality of propelling aeroplanes provided with a number of smaller aeroplanes adapted to open and close, the after edges of said propelling aeroplanes being adapted to bend upwards under the pressure of upward air, and a platform on which an operator may stand, and provided with wheels for starting and landing, substantially as described. 50
5. In a flying machine, the combination of one or more fixed aeroplanes, each composed of a number of smaller underlapping aeroplanes adapted to readily open and close with a frame provided with wheels near the middle of same, for starting and landing, and with one or more wheels at each end of said frame to support the ends of said frame on the ground in case of the machine tipping to one side or another in starting or landing, substantially as described. 55
6. In a flying machine, the combination of one or more fixed aeroplanes, composed of a number of smaller aeroplanes adapted to form one continuous surface when the air presses on their under side, and to separate and form many separate surfaces when the air presses on the top side, and means for propelling the same through the air, with a 60 box frame rising centrally above the said aeroplanes, and guys running from the upper part of said raised frame to the outer parts of said aeroplanes, for the purpose of supporting the same, substantially as described. 65
7. In a flying machine, the combination of one or more fixed aeroplanes, each composed of a number of smaller aeroplanes, adapted to close together and form one continuous surface when the wind presses on the under side, and to open and form a number of separate surfaces when the wind presses on the top side and a plurality of propelling aeroplanes provided with a number of smaller aeroplanes, each of the said smaller aeroplanes consisting of a long narrow strip of cloth or other suitable material, and a stiffening spline attached to one edge of each of said smaller aeroplanes, all substantially as described. 70
8. In a flying machine, the combination of one or more fixed aeroplanes, each composed of a number of smaller aeroplanes adapted to close together and form one continuous surface when the wind presses on the under side, and to open and form a number of separate surfaces when the wind presses on the top side, the said fixed aeroplanes being supported by a box kite frame and projecting over the edges of said frame, the edges of said fixed aeroplanes projecting to the rear being adapted to bend upwards when the wind presses on the under side, substantially as described. 75

In testimony whereof, I have signed my name to this specification, in the presence of two subscribing witnesses.

THOMAS H. GIGNILLIAT.
